ATTORNEYS.

UNITED STATES PATENT OFFICE.

MAXWELL F. GILBERT, OF PHILADELPHIA, PENNSYLVANIA, ASSIGNOR TO RICHARD-
SON & BOYNTON COMPANY, OF NEW YORK, N. Y., A CORPORATION OF NEW YORK.

HEATER.

Application filed January 14, 1926. Serial No. 81,136.

This invention relates to heaters of improved construction.

It is an object of the invention to provide a device of the type stated which will embody a construction by means of which the response of the heater to the opening of drafts will be extremely rapid, and by means of which, when the fire is "banked," the escape of coal gas will be prevented to a maximum extent.

A further object of this invention is that of furnishing a heater in which the parts accomplishing these results may be renewed with facility, these parts being protected to a maximum extent against damage.

An additional object is that of providing a heater which will efficiently perform the purposes for which it is intended, and which will also be economically and readily manufactured and easily assembled.

Other objects of the invention will in part be obvious and will in part appear hereinafter.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Figure 1 is a partly fragmentary sectional plan view of a tank heater embodying the improved construction of the present invention; and

Fig. 2 is a partly sectional side elevation thereof.

In these views the numeral 5 indicates the grate or base section of the heater, upon which the firepot section 6 is mounted. A cored or water section 7 is supported by the section 6, and in turn supports an upper section 8. Mounted upon the upper edge of the latter is a top or cover 9, from which a smokepipe collar 10 extends, this top being provided with a hinged firedoor 11.

It will be observed that all of these sections are preferably formed with flanges 12 adjacent their outer edge-portions, which flanges overlap a portion of the outer face of the next adjacent section. As a conse-

quence, these sections are prevented from being relatively displaced.

The section 8, and, if desired, the section 6, are lined with a layer of firebrick or other suitable heat-retaining and insulating material 13. By lining the lower section in this manner the firepot will be comparatively well insulated and will be heat-retentive. As a consequence, the side layer of fuel will not be readily chilled, resulting in a thickness of "dead" fuel and accumulation of clinkers, etc., and a draft will be induced through the grate and body of fuel within the heater.

With respect to the upper section 8 it will primarily be appreciated that this section is ordinarily above the upper level of the fuel bed within the heater, but will be very thoroughly heated during the operating thereof. As a consequence, when the fire is banked the lining of this section will begin to slowly give off heat, which will result in pot gases being generated. This heat will also cause the flue section to be preheated and cause the flue to draw.

Thus, when the fire is banked, coal gas will not escape, in that, while this gas is generated by the bed of fuel, it will pass up the flue and will not force itself past the fire-door. Furthermore, when the dampers and drafts are opened the furnace will readily respond, and the fire will become lively in a relatively short period of time.

It will be appreciated that with a sectional heater of this nature the lining or linings may be readily applied or renewed. In order to reduce the chipping or breaking thereof to a minimum it is preferred that certain of the sections carry inner flanges substantially in line with the inner faces of the linings 13. To this end, in the present exemplification, the top 9 is formed with a downwardly-extending flange 14, and the central section 7 is formed with an upwardly-extending flange 15, while the base section is formed with a similarly-extending flange 16. These flanges are preferably complementary to the flanges 12 associated with the sections, and the linings 13 are preferably recessed adjacent their inner faces so that the parts may properly seat.

Thus, among others, the objects of this invention are accomplished, and since certain changes may be made in the above con-

struction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

15 Having described my invention, what I claim as new and desire to secure by Letters Patent is:

1. A heater, comprising a plurality of sections, a lining of fire-resistant and heat-retentive material positioned adjacent one of said sections, and a flange forming a part of an adjacent section and overlapping certain portions of said lining.

2. A heater, including a plurality of superposed sections, a substantially horizontally-extending portion forming a part of one of said sections, and a lining of fire-resistant and heat-retentive material positioned adjacent another section and resting upon the horizontally-extending portion of said first-named section.

3. A heater, including a base, a firepot section mounted upon said base, a horizontally inwardly-extending portion forming a

part of said base, and a lining of fire-resistant and heat-retentive material positioned adjacent the inner face of said firepot section and bearing against the horizontal portion of said base.

4. A heater, including a plurality of superposed sections, a lining of fire-resistant, heat-retentive material disposed adjacent one of said sections and being formed with a recess, and a flange-portion forming a part of an adjacent heater section and extending into said recess.

5. A heater, including a plurality of superposed sections, a lining of fire-resistant, heat-retentive material applied to one of said sections, and a substantially horizontal portion formed at the upper end of a section below said first-named section, said lining resting upon said horizontal portion.

6. A heater, including a plurality of superposed sections, a lining of fire-resistant, heat-retentive material applied to one of said sections, a substantially horizontal portion formed at the upper end of a section below said first-named section, said lining resting upon said horizontal portion, a top applied to the upper edge of said first-named section, and a downwardly-extending flange forming a part of said top and extending into a recess formed in the upper edge of said lining.

In testimony whereof I affix my signature.

MAXWELL F. GILBERT.
